[57] CLAIM

The ornamental design for the electronic equipment housing, as shown and described.

DESCRIPTION

FIG. 1 is a top right and front perspective view of an electronic equipment housing showing our new design;

FIG. 2 is a bottom plan view;

FIG. 3 is a rear elevation view;

FIG. 4 is a left elevation view; and,

FIG. 5 is a top right and front perspective view of a second embodiment thereof wherein the only difference is in the appearance of the front panel.

FIG.1

FIG.2

FIG.3

FIG.4

FIG.5
